UNITED STATES PATENT OFFICE.

KENNETH HOWIE, OF NORRISTOWN, AND WILLIAM O. TAYLOR, OF LIMERICK, PENNSYLVANIA, ASSIGNORS TO WILDMAN MFG. CO., OF NORRISTOWN, PENNSYLVANIA, A CORPORATION OF PENNSYLVANIA.

PUNCH MECHANISM FOR MAKING PATTERN STRIPS.

Application filed February 16, 1923. Serial No. 619,415.

To all whom it may concern:

Be it known that we, KENNETH HOWIE and WILLIAM O. TAYLOR, citizens of the United States, and residents of Norristown 5 and Limerick, respectively, in the county of Montgomery and State of Pennsylvania, have invented certain new and useful Improvements in Punch Mechanism for Making Pattern Strips, of which the following 10 is a specification.

Our invention is designed to make pattern bands for controlling operations of a machine such as a knitting machine, wherein a plurality of yarn fingers are distributed 15 around the needle circle and feed in different colors of yarn to produce striping of the fabric.

In such a machine there may be, say, eight different yarn feeding devices at separated 20 points about the machine, and these different yarns will be in or out of service according to the striped pattern desired. There may be only one in service, or all of the eight feeds may be in service at the 25 same time, or any number between the maximum and minimum may be in service, and these may be in any desired order.

Our invention has been devised to make pattern strips, bands or sheets, which will 30 give any one of the innumerable effects that may be desired, the yarn feeds being thrown in and out in groups or singly.

The machine is shown in the accompanying drawings, in which:—

Figure 1 is a plan view.

Fig. 2 is a side view.

Fig. 3 is a sectional view from front to rear.

Fig. 4 is an end view.

Fig. 5 is a detail.

The machine comprises a series of punches 1, movable vertically in a guide frame 2, overlying the main base frame 3. These punches are pressed upwardly by 45 springs, and they are operated to punch the paper sheet which is to form the pattern band, by finger levers 4 pivoted at 5, and having cam-shaped portions 6 to rest on the heads of the punches.

50 These punches are arranged in a row transversely across the pathway along which the paper sheet, to be formed into the pattern band, is fed, and they overlie openings or dies in the base member so that

when either one is forced down, it will 55 punch an opening in the paper strip extending over the die opening. The strip is composed, preferably, of heavy paper 7, and prior to its conversion into a pattern band, it is provided along each margin with a 60 row of feed holes 7^a to be engaged by the toothed feed wheels 8, fixed to, or formed in one piece, with the sleeve 9 fixed to the shaft 9^a journaled in the bearings or ears 10 of the main frame. The paper strip is 65 introduced into the machine by sliding it over the plain upper surface of the base in the direction of the arrow and bringing its leading feed holes, one on each side, in position to be engaged by the teeth of 70 the feed wheels when these are turned. The strip is guided by upstanding sides 11 of the base. Movement to the strip can be imparted in two ways, i. e., either step by step, or continuously. 75

In the step by step movement, the steps can be made of any desired length to suit the pattern desired.

This feeding mechanism comprises a ratchet wheel 12 connected with the shaft of 80 the feed wheels so as to turn the same, but the connection is such that the feed wheels can be rotated independently of the ratchet. The ratchet is therefore loosely mounted on the shaft of the feed wheels and it is located at the left hand side of the machine at a point outside the bearing for the feed wheel shaft. It is engaged by a spring pawl 13 carried in a casing 14 on the finger lever 15 which is mounted to turn on the 85 shaft of the feed wheel, it lying between the ratchet wheel and the bearing of the shaft. The ratchet wheel is attached to the shaft 9^a by a spring pin 16 engaging a hole 17 in the side face of the ratchet. 90 This spring pin is carried by an arm 18 fixed to the feed wheel shaft outside the ratchet wheel. The spring pin has a finger button 16^a by which it can be retracted to free it from the ratchet, whereupon the 95 arm and shaft may be turned to turn the feed wheels for advancing the strip through the machine continuously, as may be desired.

When the strip is advanced by the pawl 105 and ratchet mechanism, step by step, by working the finger lever back and forth, the length of the step movement may be long

or short, according to the pattern desired. In doing this, the operator will move the finger lever away from its normal position against the stop 19, the distance of one, two 5 or any desired number of ratchet teeth. During this movement of the lever, the ratchet wheel will be held by the detent 21. Having counted off the number of spaces that he desires to advance the paper sheet, 10 by moving the finger lever back over the desired number of ratchet teeth, the operator will draw the finger lever towards himself at the front of the machine until it reaches normal position against the stop. The 15 ratchet wheel will, therefore, turn and advance the paper to its new position, and here it will rest while it is being punched. It may be punched by either one, all, or any intermediate number of punches, by depressing the desired ones of the punch levers 20 4. There are nine of these shown, one marked "C," standing for the counter which controls the operation of mechanism which counts the number of articles produced by 25 the machine, and the others are numbered from 1 to 8, corresponding to the number of feeds on the machine. If only the 1 key is depressed while the strip is standing in the position to which it has just been moved, 30 there will be only one opening in the completed strip on this imaginary line extending across the strip, and hence the pattern strip when placed in the knitting machine, will make a change only at the one feed, all 35 the other seven feeds remaining as they were. If the operator, however, had pressed down another key, or keys, additional to that numbered 1, while the paper strip is standing at rest in the position to which it has just been 40 moved, these other openings will be made in the strip in line across the same and with the hole first punched in this line, so that when the strip is used as a pattern band in the knitting machine, changes will take place 45 at all of those feeds corresponding to the position across the strip at which said holes are punched, and if eight holes are punched, there will be a change of feed at each feeding 50 point, some going out and some going into work as the case may be, to make changes in the pattern. It is entirely within the power of the operator to place the holes at the different locations across the sheet that the pattern calls for, or have only one punching 55 in the imaginary transverse line, if the pattern so demands, and it is also within his power to run the strip through the machine without operating the ratchet wheel. To do this the spring pin 16 is pulled out 60 by drawing upon finger piece 16^a and this is then used as a handle to turn the arm 18 and shaft 9^a with the wheels 8 to feed the strip as may be desired. In this continuous action, the ratchet wheel will remain stationary. The paper strip is kept in feeding 65

contact with the feed wheel 8 by a guide plate 20, Fig. 3. This is pressed by leaf springs 20^a attached to the lower side of the frame at 20^b. The plate 20 is slotted at 22, 70 Fig. 5, for the passage of the teeth of the wheels 8.

The finger levers 4 are held up in normal position by the spring pins 1 and are lined up against the cross bar 23.

The sleeve 9, in addition to having the toothed wheels 8 thereon, has an untoothed wheel 8^a to engage the central part of the strip and perform a feeding action at this point, in connection with the spring presser plate. 75

At the rear of the machine a cutting knife 24 is pivoted at 25 to cut the paper strip transversely, to the desired length, in forming the pattern band. This knife blade is pivoted to the fixed blade member 24^a which is screwed to the rear cross bar of the main frame. A guide comb for the finger levers is shown at 26. 85

The base frame is open from side to side 90 where the feed wheels are located, and the spring presser plate extends from side to side to afford a bearing for the paper strip.

What we claim is:—

1. In combination in a machine for punching strips for use as pattern bands, a series 95 of punches arranged in line transversely across the path of the strip, a guide for the strip, finger levers pivotally mounted, spring plungers operated by the finger levers, and feed means for the strip, comprising toothed members to engage openings along the margins of the strip, and means for operating said feed members manually and independent 100 of the operation of the finger levers, either step by step, or continuously, substantially 105 as described.

2. In combination in a machine for punching strips for use as pattern bands, a series 110 of punches arranged in line transversely across the path of the strip, a guide for the strip, finger levers pivotally mounted, spring plungers operated by the finger levers, and feed means for the strip, comprising toothed members to engage openings along the margins of the strip, and means for operating 115 said feed members manually, either step by step, or continuously, said means comprising a ratchet wheel, a finger lever carrying a pawl, a stop for limiting the forward movement of the finger lever, and a crank arm forming a connection between the ratchet wheel and the rotary feed members, said crank arm having a detachable connection with the ratchet wheel, substantially 120 as described.

3. In combination in a punching machine, 125 a base having a guide way for the paper strip to be punched, a row of spring punches arranged across said guide way, a frame member extending above and across said 130

guide way in which the punches are guided, finger levers pivoted to said cross frame member and extending over the spring punches, means for limiting the upper position of the levers, and hand operated feed means for the paper strip, substantially as described.

4. In combination, a base, punch mechanism including punches and finger levers, a feed wheel in rear of the punch mechanism for advancing the paper strip, a ratchet wheel connected with the feed wheel, a finger lever carrying a pawl engaging the ratchet wheel, a stop for arresting the finger lever on its feeding stroke, said finger lever being free to be moved back over the ratchet wheel to advance the same through varying degrees of angular movement in coming to the stop, and a detent for holding the feed wheel against retrograde movement, substantially as described.

5. In combination with punch mechanism, a feed wheel for advancing the paper strip to be punched, a ratchet wheel, means for connecting the ratchet wheel with and disconnecting it from the shaft of the feed wheel and for rotating the feed wheel continuously when so disconnected, and a finger lever and pawl for giving the feed wheel a step by step movement, substantially as described.

6. In combination, a base having guides for the paper strip, a punch carrying bar extending above and across the base, punches mounted therein, finger levers pivoted on the punch carrying bar at the rear of the punches and reaching forward beyond the same and bearing thereon, rotary toothed feed means in rear of the punches, and above the base and arranged over them, and a presser plate connected to the underside of the base and spring pressed upwardly to hold the paper strip in contact with the lower part of the toothed feed means, substantially as described.

7. In combination, a frame having a guide way for a paper strip, and having an opening within the guide way, feed means comprising a toothed wheel at each side of the guide way, having its teeth exposed at said opening, a presser plate on the underside of the frame to engage the paper strip through said opening and press it against the toothed wheel, said plate having slots for

the passage of the teeth, and punch mechanism arranged over the base, substantially as described.

8. In combination, a frame having a guide way for a paper strip, and having an opening within the guide way, feed means comprising a toothed wheel at each side of the guide way, having its teeth exposed at said opening, a presser plate on the underside of the frame to engage the paper strip through said opening and press it against the toothed wheel, said feed means also comprising a plain periphery wheel moving in unison with the toothed wheels and engaging the central part of the paper strip, the said presser plate holding the paper strip against the plain wheel, and punch mechanism arranged over the base, substantially as described.

9. In combination, a base frame having side guides for a paper strip, punch mechanism, paper feed mechanism comprising feed wheels on a sleeve, a shaft carrying said sleeve and mounted in bearings at the sides of the frame, a finger lever mounted loosely on an extension of said shaft outside said bearing, a ratchet wheel also loosely mounted on said shaft extension, a crank arm mounted on said shaft extension and fixed thereto, and having a detachable connection with the ratchet wheel, a pawl carried by the finger lever engaging the ratchet wheel, and a detent engaging the ratchet wheel, substantially as described.

10. In combination with punch mechanism, a feed wheel for advancing the paper strip to be punched, a ratchet wheel, a finger lever having a pawl to engage the ratchet, said finger lever being movable to different degrees for advancing the said ratchet a varying number of teeth spaces, means for connecting the ratchet wheel with, and disconnecting it from, the shaft of the said wheel, and for rotating the said wheel continuously when so disconnected, said punch mechanism having finger levers for operating the same, and said feed mechanism being operable independently of the punch mechanism, substantially as described.

In testimony whereof, we affix our signatures.

KENNETH HOWIE.
WILLIAM O. TAYLOR.
